CLAIM

I claim the ornamental design for an exercise track for flexing and extending legs, as shown and described.

DESCRIPTION

FIG. 1 is a front/top isometric view of an exercise apparatus embodying my design.

FIG. 2 is a top/side isometric view of an exercise apparatus device embodying my design.

FIG. 3 is a rear isometric view of an exercise track for flexing and extending legs embodying my design.

FIG. 4 is a top view of an exercise track for flexing and extending legs embodying my design.

FIG. 5 is a bottom view of an exercise apparatus device cover embodying my design.

FIG. 6 is a left side elevation view of an exercise apparatus device embodying my design.

FIG. 7 is a right side elevation view of an exercise track for flexing and extending legs embodying my design.

FIG. 8 is a front elevation view of an exercise track for flexing and extending legs embodying my design; and,

FIG. 9 is a rear elevation view of an exercise track for flexing and extending legs embodying my design.

The broken lines represent boundaries of the claimed design and form no part thereof.
